UNITED STATES PATENT OFFICE.

SAMUEL KING, OF CARLINGFORD, NEW SOUTH WALES, AUSTRALIA.

JIB-CRANE EXCAVATOR.

Application filed July 3, 1924, Serial No. 724,098, and in Australia July 31, 1923.

This invention relates to improvements in jib-crane excavators, and has been devised with the view to providing apparatus for the purpose which can be attached to an existing type of crane, either driven by steam, oil engine or electric power, with a minimum amount of alteration thereto.

According to the invention, I provide a ram, in the case of a steam driven crane, mounted on a suitable base plate which can be rigidly secured to the jib of the crane a short distance from its pivoted point. To the upper portion or swan neck of the jib, are attached two or more stay rods or arms which extend downwardly and are pivoted about midway to a runway or ladder which forms the excavator track. The upper end of this ladder is coupled to the ram cross-head and the lower end turned outwardly in a short radius for some distance. Adapted to travel in this ladder or runway, is a carriage, the excavator bucket being pivoted or hinged to said carriage. A catch or trigger is positioned at the upper portion of the ladder and is adapted to engage with the first or leading axle of the excavator carriage when at the top of its travel, to hold same while it is being emptied. A winding drum and a winding rope are provided on the crane, the end of the rope being passed over suitable pulleys on the bucket, and secured to eye bolts on the carriage. The ram is of the double acting type and is provided with control valves on each end of the cylinder, said valves being chain and wheel controlled.

A further chain and wheel is provided running parallel with the ram, and has stops so that on the ram being driven outwardly, the cross head suitably provided with an arm or the like, will engage such stops to cut off the valve controlling the outward travel of the ram.

In the case of oil or electric power, I provide racks and gears, or other suitable means, in place of the steam ram, to move the upper end of the ladder of the excavator.

But in order that my invention may be more clearly comprehended, I will now refer to the accompanying drawings in which is illustrated an excavator as applied to a steam jib crane.

Figure 1, is a side elevation of the excavator with the bucket in the lowered position, the dotted lines illustrating the bucket when raised, and

Figure 2 is an enlarged side elevation of the excavator with the bucket cutting into the side of an embankment, the dotted lines illustrating the bucket discharging. 60

Figure 3, is a side elevation of the excavator bucket and the bucket carriage, in the closed position, while

Figure 4, is a similar view with the bucket in the open position for discharging. 65

Figure 5, is a part sectional elevation illustrating the rear wheel of the bucket carriage in the channel or side member of the runway or ladder.

Figure 6 is a part sectional side elevation 70 of the locking means for the bucket carriage.

Figures 7 and 8, are part side and plan views respectively of the steam ram.

The same numerals indicate like parts 75 throughout the drawings.

11 is the steam crane with swan neck jib 12, while 13 are the supports or stay rods to which is pivoted about midway, the excavator ladder or runway 14. This ladder comprises two side channels in which are 80 adapted to run the wheels 15 of the bucket carriage 16 to which is hinged at 17 the bucket 18. This bucket 18 is provided with teeth 19 at its forward end and has pulley wheels 20 at each side over which pass the 85 pulling rope 21, the end of which is secured to the eye bolts 22. The ladder 14 is turned in a short radius outwardly at 23 at its lower end and is provided at its upper end 24 with means for pivotally connecting it to 90 the ram crosshead 25. The ram 26 has valves 27 and 28 one at each end of the cylinder, which are controlled by the chain 29 and the wheels 30 moved by the operator on the crane 11. Chain 35, provided with stops 95 36 with which the arm 37 on the ram crosshead 25 is adapted to contact, control the opening and closing of the valves 27 and 28 while the ram is in operation.

A pulley 31 is provided on the jib 12 over 100 which the pulling rope 21 passes to the crane winding drum. A trigger or locking means 32 is provided on the upper portion of the ladder 14, which engages the front or leading axle 33 of the bucket carriage 16 when the bucket is in the raised position, said trigger 32 being unlocked when desired, by the operator working the rope 34. 38 represents a track on which the crane is adapted to travel, and 39 represents a truck or vehicle for removing the excavated earth. 110

In operation, the excavator ladder 14 is

swung into position, the ram 26 being in the inward position, and the bucket 18 lowered to its fullest extent. The bucket carriage 16 runs out on the radius 23 of the ladder, which 5 brings the teeth 19 of the bucket approximately horizontal. The ladder 14 bears its weight at the lower end of the bucket. The ram 26 is then operated which forces the teeth 19 of the bucket into the embankment 10 and the pulling rope 21 is then wound up while the weight of the ladder together with that of the bucket acts to force the bucket to dig into the ground as will be understood. This operation scoops earth into the bucket 15 until the top of the embankment is reached. The bucket 18, when it has reached the position shown in Figures 1, 2, and 6 is locked by reason of the axle 33 raising the trigger 32 which falls over the axle and so retains 20 the carriage 16 in this position. The pulling rope 21 is then slightly lowered which allows the bucket 18 to swing down upon its hinges 17 thereby discharging the excavated earth into a truck or vessel 39 or the like. 25 The operator may then release the ram 26, unlock the trigger 32 by operating the rope 34, thereby permitting the bucket 18 to descend by gravity to its lowest position, when the operation of excavating is again repeated. The crane 11 may be moved along the track 38 after each operation so as to obtain 30 an even cutting of the bank.

I claim.

1. An excavator comprising a crane having a jib, a ram on the crane, a member having its end pivotally connected to the movable member of the ram for movement thereby on the crane and having an outwardly turned lower end, a stay connecting the 40 crane and said member at a point midway the ends of said member, means to raise and lower the crane and to also correspondingly move said member, a carriage mounted on said member for movement longitudinally thereof, 45 a bucket on the underside of said member

pivots connected at its outer, closed end to said carriage and having its inner, open end presented toward the crane, a cord attached to the carriage and slidably connected to the open end of the bucket, and means to 50 operate said cord to first hold the bucket substantially parallel with the carriage, to then draw the bucket and carriage upwardly on the underside of said member and to finally release said bucket to enable it to swing 55 downwardly and outwardly and discharge its contents from its open end when the bucket has reached a desired elevation.

2. An excavator comprising a crane having a jib, a member pivotally connected to the 60 crane and having an outwardly turned lower end, a stay connecting the crane and said member, means to raise and lower the crane and to also correspondingly move said member, a carriage mounted on said member for 65 movement longitudinally thereof, a bucket on the underside of said member pivotally connected at its outer, closed end to said carriage and having its inner, open end presented toward the crane, a cord attached to the carriage and slidably connected to the open end of the bucket, and means to operate 70 said cord to first hold the bucket substantially parallel with the carriage, to then draw the bucket and carriage upwardly on the underside of said member and to finally release said bucket to enable it to swing downwardly and outwardly and discharge its contents 75 from its open end when the bucket has reached a desired elevation, and means to detachably hold the carriage and hence the bucket in such elevated position, said means comprising a gravitating trigger pivotally mounted on said member and engageable with a member of said carriage, and a cord to 80 operate said trigger.

In testimony whereof I have hereunto set my hand.

SAMUEL KING.
